[57] CLAIM

The ornamental design for an adjustable floodlight, as shown and described.

DESCRIPTION

FIG. 1 is a top, rear perspective view of an adjustable floodlight showing my new design;

FIG. 2 is a top plan view thereof on an enlarged scale;

FIG. 3 is a rear elevational view thereof on an enlarged scale;

FIG. 4 is a right hand side elevational view thereof on an enlarged scale;

FIG. 5 is a front elevational view thereof on an enlarged scale;

FIG. 6 is a bottom plan view thereof on an enlarged scale;

FIG. 7 is a top, rear perspective view of a second embodiment of my new design;

FIG. 8 is a top plan view thereof on an enlarged scale;

FIG. 9 is a rear elevational view thereof on an enlarged scale;

FIG. 10 is a right hand side elevational view thereof on an enlarged scale;

FIG. 11 is a front elevational view thereof on an enlarged scale;

FIG. 12 is a bottom plan view thereof on an enlarged scale;

FIG. 13 is a left hand side elevational view of my first embodiment on an enlarged scale; and

FIG. 14 is a left hand side elevational view of my second embodiment on an enlarged scale.
